ABSTRACT OF THE DISCLOSURE

A cabinet of a shot-blasting apparatus comprising a primary portion having a lower part in the shape of an inverted pyramid constituting the cabinet base and a secondary portion which sits over the primary portion, the primary portion having an upper part which includes a rear wall and a pair of side walls the top edges of which are inclined downwardly towards the front, but having no front wall, the secondary portion having a rear wall which is hinged to the rear wall of the upper part of the primary portion, a front and side walls the lower edges of which are inclined to correspond in inclination to the top edges of the side walls of the upper part of the primary portion and which rest upon such side walls when the secondary portion is closed upon said primary portion. The front of the secondary portion of the cabinet may include a window and access openings fitted with flexible seals for manual operations.

The invention relates to shot-blasting apparatus of the kind which includes a cabinet adapted to provide a chamber for accommodating blasting equipment and articles to be dealt with by such equipment.

The object of the present invention is the provision of new or improved shot-blasting apparatus and is particularly concerned with the cabinet portion thereof and with related parts in order that apparatus according to the invention possesses considerable advantages over conventional apparatus, advantages which will be herein-after referred to.

According to the present invention there is provided shot-blasting apparatus including a cabinet containing shot blasting tool means and having a viewing window so that the shot blasting may be viewed, said cabinet comprising a primary portion made up of a lower part in the shape of an inverted pyramid and an upper part comprising a rear wall and a pair of side walls of which the top edges are inclined downwardly towards the front of the cabinet so that said upper portion is devoid of a front wall, and a secondary portion in the form of a hollow open-bottomed cap which has a rear wall hinged to the rear wall of the upper part of the primary portion, a front wall and a pair of side walls the lower edges of which are inclined to correspond to the inclination of the top edges of the side walls of the upper part of the primary portion so that said lower edges rest on said upper edges when the cap is hinged to close the upper part of the primary portion.

In order that the invention may be fully and clearly comprehended the same will now be described with reference to the accompanying drawings, in which:

FIG. 1 is a front view of shot-blasting apparatus according to the invention, with the canopy thereof closed.

FIG. 2 is a sectional side view of the upper part of the apparatus shown in FIG. 1 on the line II—II of the latter figure, but with the canopy opened. The closed position of the canopy is indicated in broken lines.

FIG. 3 is a section of a fragment of the canopy of the apparatus, drawn to large scale.

The cabinet of the apparatus comprises a base or primary portion 1, provided with legs 2, and a canopy or

2

secondary portion 3. If desired, the portion 1 could be arranged to be supported on a pedestal of any suitable configuration.

The primary portion 1 has a lower of hollow inverted substantially pyramidal shape and an upper part which includes a pair of opposing side walls 5 and an interconnecting rear wall 6, the top edges of the side walls being inclined downwardly towards the front in such a manner that they terminate at the front so that the upper part of the primary portion is devoid of any front wall.

Hinged to the rear wall 6 of the upper part of the primary portion 1 is the secondary portion 3 in the form of a canopy or cover which is dished and has a top 7 with an inclined panel 8, vertical side walls 9 whose lower edges are inclined to correspond to inclination of the upper edges of the side walls 5 of the upper part of the primary portion, a vertical front wall 10 and a similar rear wall 11.

15 The panel 8 contains a transparent observation window 12 and the front wall 10 incorporates a pair of appropriately shaped openings each covered by a flexible sealing member 13 having slits therein for permitting an operator to pass his or her hands into the blast chamber formed when the canopy is closed with the inclined edges of the walls 9 resting on the inclined edges of walls 5, as in FIG. 1. Also secured to the wall 10 is a handle 14 and, if desired, means 3A, 3B may be provided for latching or securing the canopy in a closed position.

20 30 The amount by which the canopy 3 may be opened may be determined by any suitable means such as by a supporting bracket 15 secured to wall 6, or by lever mechanism indicated at 15A, 15B, 15C. Also, manual opening of the canopy may be assisted by the provision of a counterweight, pneumatic or dash-pot device or by a spring, any of which means may also retain the canopy in its open position.

25 35 Housed in the shot-blasting chamber of the apparatus is a suitable shot-blasting gun 16 and compressed air and abrasive supply pipes 17 and 18. The lower end of the lower part of the primary portion 1 has an opening therein to which is attached one end of a pipe 18A for sucking away abrasive or like shot-blasting material from the interior of the blast chamber of the apparatus for subsequent recirculation in the usual manner.

40 45 The shot-blasting gun 16 may be controlled by any suitable known kind of valve mechanism which may be manually operated or be operated by foot-pedal 19.

50 55 It is, however, preferred to link the valve for controlling the shot-blasting gun 16 to the canopy 3 in such a manner that when the canopy is closed the said valve is automatically opened and vice-versa. To this end the valve may be solenoid operated and the energisation of the valve is under the influence of a micros-switch 50 which is actuated by the canopy 3 when same is in the closed position thereby causing the valve to be opened.

I claim:

1. Shot-blasting apparatus including a cabinet containing shot blasting tool means and having a viewing window so that the shot blasting may be viewed, said cabinet comprising a primary portion made up of a lower part in the shape of an inverted pyramid and an upper part comprising a rear wall and a pair of side walls of which the top edges are inclined downwardly towards the front of the cabinet so that said upper portion is devoid of a front wall, and a secondary portion in the form of a hollow open-bottomed cap which has a rear wall hinged to the rear wall of the upper part of the primary portion, a front wall and a pair of side walls the lower edges of which are inclined to correspond to the inclination of the top edges of the side walls of the upper part of the primary portion so that said lower edges rest on said upper edges when the cap is hinged to close the upper part of the primary portion.

lower edges rest on said upper edges when the cap is hinged to close the upper part of the primary portion.

2. Apparatus according to claim 1, further including limiting means for limiting the amount by which the secondary portion can be hinged on the primary portion in a direction to open the upper part of the primary portion.

3. Apparatus according to claim 2, wherein said limiting means comprises a bracket attached at the rear wall of the upper part of the primary portion.

4. Apparatus according to claim 2, wherein said limiting means comprises a lever mechanism connected between said primary and secondary portions.

5. Apparatus according to claim 1, further including valve means through which the shot blasting medium is supplied to the tool means and control means controlling the operation of the valve means and hence the supply of shot blasting medium to said tool means.

6. Apparatus according to claim 5, wherein said control means is switch means operable by the secondary portion of the cabinet when same is in position closing the upper part of the primary portion so that the valve means can be opened only when the cabinet is closed.

7. Apparatus according to claim 1, wherein the shot blasting tool means is mounted above the inclined top edges of the upper part of the primary portion so that such tool is completely exposed for access when the secondary portion is hinged to the open position.

8. Apparatus according to claim 1, wherein the lower part of the primary portion at the bottom thereof, is provided with an opening adapted for coupling to means for sucking shot-blasting medium from said lower part for recirculation in the apparatus.

9. Shot-blasting apparatus according to claim 1, wherein said cabinet further including openings provided with flexible seals which enable insertion of an operator's hands into the cabinet during operation of the apparatus yet seal around his arms to prevent loss of shot blasting medium through the opening.

10. Shot-blasting apparatus according to claim 1, wherein the lower edges of the side walls and the front wall of the secondary portion are directed downwardly and inwardly towards the interior of the cabinet so that shot blasting medium will not collect therein.
